Attorney

UNITED STATES PATENT OFFICE.

MERLE EDWIN HENDERSON, OF FORT VALLEY, GEORGIA.

HOSE-COUPING.

SPECIFICATION forming part of Letters Patent No. 744,073, dated November 17, 1903.

Application filed July 18, 1903. Serial No. 165,796. (No model.)

To all whom it may concern:

Be it known that I, MERLE EDWIN HENDERSON, a citizen of the United States, residing at Fort Valley, in the county of Houston and State of Georgia, have invented certain new and useful Improvements in Hose-Couplings; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in hose-coupler; and it consists in the provision of simple and efficient means for quickly and securely coupling the ends of hose together, and more specifically comprises two collars or bands which have hinged connection, and one of said bands carrying a lever, while the other is provided with a tongue designed to be engaged by a spring-actuated pawl carried by the lever, whereby as the lever is thrown down over the tongue the two ends of the coupler are brought together by cam action of parts of the coupler, thus producing a tight joint.

The invention consists, further, in other details of construction and in arrangements of parts, which will be hereinafter fully described and then specifically defined in the appended claim.

My invention is illustrated in the accompanying drawings, in which—

Figure 1 is a side elevation of my improved coupler, the lever being shown in dotted lines in the position it assumes when not in a connected relation. Fig. 2 is a central longitudinal sectional view through the coupler.

Reference now being had to the details of the drawings by letter, A and A' designate two coupling-heads having flanges *a*, intermediate which washers *B* are adapted to be placed before the heads are coupled together.

D and E designate collars or bands, one of which, D, is provided with a tongue D', having a cam edge *d* and a shoulder *d'*, adapted to rest over the flange of one of the coupling-heads when the latter are held together. Said cam edge has a notch *F* therein adapted to be engaged by a pawl about to be described.

Integral with the collar D at a position diametrically opposite said tongue is a hook G, which is adapted to engage an integral eye H, which projects at right angles from a lug E' on the collar E, thus forming a hinged connection between the two collars. A second lug E² projects from the collar E diametrically opposite said lug E' and carries a pin N, upon which the forked end of the lever R is mounted. Said lever R carries a spring-actuated dog T, which is mounted in a central chambered portion of the handle, as shown clearly in the drawings, and is held in the space intermediate the forked ends of the lever by means of the spring S, the ends of which spring bear between the end walls of a recess Q in the lever. A portion of the circumference of said dog is threaded, as at J, and an adjusting-nut L is mounted upon said threaded circumference and adapted to regulate the tension of said spring and the throw of the dog. The crotch of the lever intermediate said arms is inclined, as at W, against which inclined surface the cam edge of said tongue is adapted to contact as the lever is thrown down against the coupling-head, which movement will have a tendency to force the ends of the couplers with considerable pressure against the washer interposed between the coupler-heads, thereby producing a tight joint.

In applying the device the collars D and E are applied to the coupler-heads before the latter are put together, and as the coupler-heads are brought together the hook on one of said collars is caught in the eye upon the other one and the lever pushed down upon said tongue, and after the two heads have been tightly forced together and the end of the dog comes in contact with the notch in said cam edge the spring will throw the dog into the notch and the coupler-heads will be securely locked together.

While I have shown a particular construction of apparatus embodying my coupler device, it will be understood that I may make alterations in the detailed construction of the same, if desired, without departing from the spirit of the invention.

Having thus fully described my invention, what I claim as new, and desire to secure by Letters Patent, is—

A hose-coupler comprising a collar E having a lug with an apertured projecting portion, a handle having arms pivoted to lugs upon said collar, a second collar D having an integral hook projecting therefrom adapted to engage the aperture in said projection, an integral catch projecting from the collar D at a position diametrically opposite said hook projection and having one edge thereof inclined, a cross-piece having an inclined edge, as at W, upon said handle, conforming to the inclined surface of said catch and adapted to have a wedging action against the same as

the lever is thrown toward the coupling, a spring-pressed bolt mounted in said handle, 15 with its inner end beveled and adapted to engage a notch in said catch, an adjusting-nut mounted on the outer threaded end of said bolt, adapted to regulate the throw of the latter, as set forth.

In testimony whereof I hereunto affix my signature in presence of two witnesses.

MERLE EDWIN HENDERSON.
